CLAIM

The ornamental design for a “watch,” as shown and described.

DESCRIPTION

FIG. 1 is a perspective view of watch showing my new design;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof;
FIG. 8 is an enlarged cross-sectional view taken along line 8-8 shown in FIG. 2;
FIG. 9 is an enlarged exploded perspective view of the watch; and,
FIG. 10 is a reference view showing the watch in use.
The broken lines depict environment only and form no part of the claimed design.

1 Claim, 8 Drawing Sheets
